Attorney

UNITED STATES PATENT OFFICE.

AUGUSTUS F. FIBIGER, OF SPOKANE, WASHINGTON, ASSIGNOR OF ONE-TENTH TO HARVE H. PHIPPS AND ELMER J. EDWARDS, BOTH OF SPOKANE, WASHINGTON, AND FIVE-TENTHS TO CHARLES FIBIGER, TRUSTEE.

SWIMMING SHOE.

Application filed February 6, 1928. Serial No 252,082.

My present invention relates to an improved swimming shoe adapted to be worn by the swimmer for the purpose of increasing the effect and power applied by the leg stroke of the swimmer and thereby increase the speed of the swimmer. In carrying out my invention I utilize a shoe that may be of canvas or other suitable material and which is provided with usual lacing or fastening devices, and the sole of the shoe is fashioned with surrounding extensions at front, rear and sides. These extensions form a normally flat web of flexible material as rubber that is designed to fold or bend along the longitudinal center line of the foot as the leg and foot are moved forward on the swimming stroke, and to return to flat position and remain extended during the backward movement or kick of the swimming stroke for the purpose of increasing the propulsive effect of the stroke.

The web is provided with resilient reinforcing members that facilitate the movement and actions of the web and these elements are so distributed throughout the web as to secure the most effective service of the web during the swimming stroke.

My invention consists in certain novel combinations and arrangements of parts as will hereinafter be more fully set forth and claimed.

In the accompanying drawings I have illustrated one complete example of the physical embodiment of my invention in which the parts are combined and arranged according to the best mode I have so far devised for the practical application of the principles of my invention.

Figure 1 is a plan view of a shoe and web according to my invention and shown in working position.

Fig. 2 is a view in side elevation showing the web cut along the longitudinal line 2—2 of Fig. 1.

Fig. 3 is a transverse vertical sectional view at line 3—3 of Fig. 1 and showing by dotted lines the flexed position of the web.

Fig. 4 is an enlarged detail sectional view at the upper edge in Fig. 1 and along the dotted line 3—3.

In carrying out my invention I utilize a conventional swimming shoe as 1 that may

be of leather or other suitable material and provided with a lace or other fastening device as 2.

The sole of the shoe is extended in all directions from the shoe to form a web 3 and this web is preferably of rubber. As shown, the web extends in front of the toe and back of the heel as well as at both sides of the shoe. The web is of approximate elliptical form and along its two sides are provided a pair of wires 4, 4 that extend around adjacent to the edge of the web but terminate at their ends at the front and rear ends of the web and at opposite sides of the longitudinal center of the shoe and web. The wires are embedded within the web and the latter is provided with a bead 5 that projects slightly below the underface of the web.

Along the longitudinal center of the shoe and spaced at both sides thereof is arranged a pair of longitudinal extending reinforcing blades 6. These blades are of resilient metal and they extend from the front edge to the rear edge of the blade. Due to this construction and arrangement the web may be flexed or bent with a hinge movement along its longitudinal center line as indicated by the dotted lines in Fig. 3. This flexing movement permits the web to be folded along its center line when the leg is being drawn forward, and the web of course is extended flat when the leg is being kicked backwardly for the pushing stroke of the swimmer. The web may be reinforced with a suitable number of radially extending resilient blades 7 and these blades extend from near the longitudinal blades 6 out to the wire edge members 4.

As thus constructed it will be apparent that the swimming shoes of my device when worn by the swimmer will enable him to secure an enhancing propulsive effect from his swimming stroke over that secured without the use of these swimming shoes.

Having thus fully described my invention what I claim as new and desire to secure by Letters Patent is:

1. A swimming shoe having a web extending therefrom, a pair of longitudinally extending spaced resilient blades embedded in the web to permit the web to flex along the longitudinal center of the shoe, wire reinforce-

ing elements along the side edges of the web, and radially extending resilient blades between the longitudinally extending blades and said wire strips.

5. 2. A swimming shoe having a web extending therefrom, a pair of longitudinally extending spaced resilient blades embedded in

the web to permit the web to flex along its longitudinal center, and wire reinforcing elements along the side edges of the web 10 having their ends connected to an adjoining resilient blade.

In testimony whereof I affix my signature.

AUGUSTUS F. FIBIGER.
